US00D648137S

(12) **United States Design Patent**
Olson et al.

(10) **Patent No.:** US D648,137 S
(45) **Date of Patent:** ** Nov. 8, 2011

(54) **ABSORBENT PAPER**

(75) Inventors: **Steven R. Olson**, Menasha, WI (US);
Ayanna M. Bernard, Neenah, WI (US);
Michael D. Wishneski, Oconto, WI
(US); **Donald J. Holewinski**,
Hortonville, WI (US)

(73) Assignee: **Georgia-Pacific Consumer Products**
LP, Atlanta, GA (US)

(**) Term: **14 Years**

(21) Appl. No.: **29/362,235**

(22) Filed: **May 21, 2010**

(51) LOC (9) Cl. **05-06**

(52) U.S. Cl. **D5/57**; D5/53

(58) **Field of Classification Search** D5/1, 3,
D5/4, 7, 47, 53, 54, 57–63, 99; D6/582,

(57) **CLAIM**

The ornamental design for an absorbent paper, as shown and described.

DESCRIPTION

The sole FIGURE is a plan view of the absorbent paper. The broken line boundaries and the spaces within the broken lines form no part of the claimed design.

1 Claim, 1 Drawing Sheet
